INSULATED COMBINED FOOD HOLDER AND SERVER

Henry G. Farris, 11417 N. May Ave.,
Oklahoma City, Okla. 73120

Filed Apr. 1, 1971, Ser. No. 130,567

Term of patent 14 years

Int. Cl. D7

U.S. Cl. D7—77

— I —. 1

— I —. 2

FIG. 1 is a top front perspective view of an insulated combined food holder and server showing my new design;

FIG. 2 is a top rear perspective view thereof showing the side opposite that of FIG. 1;

FIG. 3 is a bottom plan view thereof;

FIG. 4 is an exploded enlarged view in section taken along the longitudinal center thereof;

FIG. 5 is a top perspective view of the lower portion thereof of FIG. 4; and

FIG. 6 is a perspective interior view of the upper portion thereof of FIG. 4.

I claim:

The ornamental design for an insulated combined food holder and server, substantially as shown.
